UNITED STATES PATENT OFFICE.

HANS PETER MARTIN NIELSEN, OF CHICAGO, ILLINOIS.

FAN ATTACHMENT FOR ROCKING-CHAIRS

1,174,436.

Specification of Letters Patent. Patented Mar. 7, 1916.

Application filed January 8, 1915. Serial No. 1,130.

To all whom it may concern:

Be it known that I, HANS PETER MARTIN NIELSEN, a subject of the King of Denmark, residing at Chicago, in the county of Cook 5 and State of Illinois, have invented certain new and useful Improvements in Fan Attachments for Rocking-Chairs, of which the following is a specification.

This invention relates to improvements 10 in fan attachments for rocking chairs and its object is to provide a simple and inexpensive mechanism which can readily be attached to a rocking chair and automatically operated by the motion of the chair when 15 the same is in use.

With the foregoing and other objects in view the invention consists in the combination and arrangement of parts to be hereinafter fully described in the following 20 specification, pointed out in the claims and illustrated in the accompanying drawings which form part of said specification and in which—

Figure 1 is a side elevation of my invention applied to a rocking chair. Fig. 2 is 25 a front view of the attachment. Fig. 3 is a side view of the lower portion of the device. Fig. 4 is an enlarged perspective view of the pawl. Fig. 5 is an enlarged view of 30 the upper portion of the device with one side of the housing removed. Fig. 6 is a plan of Fig. 5 with the housing in section. Fig. 7 is a view of one of the gear shafts employed.

Like reference characters indicate corresponding parts throughout the several views.

The reference numeral 1 designates the 40 chair to one rocker of which a standard 2 is secured that is formed with an elongated slot 3 and the upper end of which terminates in a head 4 in which a curved slot 5 is formed. A set screw 6 extends through the slotted portion 3 of the standard 2 and 45 serves as a guide for said standard, said screw being carried by a bracket 7 carried by the chair. To this standard 2 adjacent the head 4 an arm 8 is bolted as at 9 and said arm is provided with a pin 10 that 50 rides in the slotted portion 5 of the head 4; the upper end of arm 8 carrying a housing 11 open as at 12 at one end, the sides of the housing being bolted together as at 13. A fan shaft 14 journaled in the sides of the 55 housing carries a rotary fan 15 and said shaft is further provided with a cog wheel

16 in mesh with a gear wheel 17 carried upon shaft 18 also journaled in the housing and said shaft 18 is further provided with a cog wheel 19 in mesh with a gear wheel 20 carried by shaft 21 also journaled in the housing. A lever 22 is loose upon shaft 21 and a spring 23 disposed upon said shaft has one end secured to the side of the housing and the other to the lever 22. In the 60 free termination of the lever 22 a pin 24 is carried and upon the same a casting 25 is loosely carried, said casting carrying a weight 26 and a pawl 27 adapted for engagement with the teeth of the gear wheel 20. A 70 rod 28 connects the pin 24 with a lever 29 pivoted at 30 to the standard 2 and the opposite end of said lever is pivotally connected to a rod 31, which extends through a bearing 32 connected to the standard 2, 75 that carries a roller 33 that rests upon the floor.

As the chair moves backward upon its rockers the standard 2 is drawn toward the 80 floor causing the bearing 32 to ride downward over the rod 31 and causing the connections of that rod to pull downward upon the pin 24 thus causing the pawl 27 to rotate the gear wheel 20 and shaft 21 and gear 20 in mesh with cog wheel 19 will rotate shaft 18 and gear wheel 17 which through its connection with cog wheel 16 will rotate the fan shaft 14 thus setting the fan in motion. The upward movement of the 85 rocker will reverse this movement and the 90 spring 23 will raise the pawl out of engagement with the wheel 20 and move it back into position for the next downward movement of said rocker.

What is claimed is:—

1. In a fan attachment for a rocking chair, a slotted standard secured to one chair rocker and terminating at its free extremity in a head formed with a curved slot, a guide for said standard disposed in the slotted portion thereof and carried by said chair, an arm terminally secured to said standard and slidably associated with the slotted portion of the head thereof, a housing carried by said arm, a shafted fan carried by said housing, gearing disposed in said housing and operatively associated with said fan, a lever loose upon one of the shafts of said gearing, connection between said lever and gearing whereby movement of the former in one direction will impart motion to the latter, a spring connecting said lever and

the housing whereby the former may be returned to initial position after each engagement with said gearing, a rod operatively associated with said standard and having a roller bearing on the floor and connection between said lever and rod whereby movement will be imparted to the former as the chair and standard are moved in one direction.

- 13 2. In a fan attachment for a rocking chair, a housing open at one end, movable supporting means for said housing carried by said chair, a shafted fan carried by said housing, gearing carried by said housing and operatively associated with said fan, a lever loose upon one of the shafts of said gearing, means carried by said lever for engage-

ment with said gearing to impart motion to the same as said lever is moved in one direction, a lever pivoted to said housing supporting means, a rod pivoted to said lever and having a roller bearing on the floor and connection between said lever and the first named lever whereby movement is imparted to the latter member through movement of the chair.

20 In testimony that I claim the foregoing as my own I have hereto affixed my signature in the presence of two subscribing witnesses.

HANS PETER MARTIN NIELSEN.
